COMPRESSOR

Costin Lane Densham, Chaldon, England, assignor to Wade Engineering Limited

Application April 1, 1949, Serial No. 84,897
In Great Britain April 7, 1948

3 Claims. (Cl. 230—138)

1

The invention relates to a compressor for elastic fluids of the kind having a pair of rotors arranged for rotation in opposite senses within a ported casing, each rotor having at least one recessed portion forming a rotating chamber for transferring fluid from an inlet port to an outlet port.

The most common type of elastic fluid compressor such as is used for internal combustion engine superchargers or compressors for the atmospheres in aircraft cabins is a blower of the Roots type. In such compressors the elastic fluid is carried through the casing by a pair of rotors and it is impossible to provide compression within the casing since the effect of the moving rotors is merely to produce displacement of the fluid. Consequently the compression produced by such blowers is due to a throttle in the outlet passage.

Proposals have been made for blowers having rotors with sliding vanes on rotors working within elliptical casings so as to produce compression within the blower casing but such arrangements have not been satisfactory mechanically.

The object of the present invention is to produce a compressor having the mechanical advantages of the well-known Roots type but in which it is possible to provide a variable compression within the casing.

In accordance with the invention, in a compressor as hereinbefore specified, the rotors are so formed and driven that a projecting part of one rotor progressively enters the recessed part of the other rotor during its movement from the inlet port towards the outlet port so that the gas within the rotating chamber is compressed progressively as the chamber rotates and the chamber has an outlet port and means for varying the timing of the opening of the port so that a selected compression may be attained before the fluid can leave the rotating chamber.

Conveniently, at one end of each rotor there is provided a ported web, and a movable ported plate is interposed between the ported web and an end wall of the casing to provide the necessary timing means.

In one form the periphery of each rotor may comprise one projecting lobe and one recess, the lobe and recess both having a part cylindrical surface and being connected by a portion contoured to obey the gearing law. A compressor having such rotors gives two compression impulses per revolution, i. e. one impulse per rotor. Such a compressor can be constructed to give compression ratios of the order of 10:1, but where lower compression ratios are sufficient, rotors hav-

2

ing two or more lobes may be used, and the compressor gives four or more compression impulses per revolution.

The invention is further illustrated in the accompanying drawings in which: Fig. 1 is a perspective view of the compressor in accordance with the invention, Fig. 2 is a similar view with the casing partly dismantled, Fig. 3 is a longitudinal section of the compressor shown in Fig. 1, Fig. 4 is a section along the lines 4—4 of Fig. 3 and Fig. 5 is a similar section showing a modified shape of rotor.

Referring to Figs. 1 to 4, the compressor comprises a casing having a main body 10 with inlet ports 20, 21 and detachable end caps 11, 12 which are internally ducted to provide an outlet for gas compressed in the casing, the outlet gases being exhausted into a manifold 13. The detachable end caps 11, 12 house bearings for shafts 14, 15 on which are mounted rotors 16, 17. The shaft 15 is extended at 15' to form a driving connection and within the end cap 11 are accommodated gear wheels 18, 19 which drive the shafts 14, 15 and rotors 16, 17 in opposite rotational senses. Each rotor (see Fig. 4) has two lobes 16', 16'' and 17', 17'' between which are recesses. The lobes and recesses have part cylindrical surfaces of differing diameter which contact along the line where they intersect the axial plane of the shafts 14, 15. Inlet ports 20, 21 are provided midway of the side wall of the casing 10 opposite the axes of the shafts 14, 15, respectively. At one end of the rotor 16 is fixed a web 24 having a port 25 the other rotor having at the other end a similar web 26 with a port 27.

The end cap 11 has an end wall 28 with a port 29 which communicates with a flanged outlet 30 to which the manifold 13 is bolted. Interposed between the end plate 24 on the rotor 16 and the end wall 28 is a rotatable plate 31 having a port 32. A similar rotatable plate 33 having a port 34 is carried in the other end cap 12, the plate 33 however being associated with the rotor 17 (see Figs. 3 and 4).

In operation the two rotors 16, 17 are rotated in opposite directions as shown in Fig. 4 and it will be appreciated that in Fig. 4 the recess in the rotor 16 lying adjacent the inlet port 20 is full of air and the inlet port 20 is about to be closed by the lobe 16'', while the corresponding recess in the rotor 17 is filling with air from inlet port 21. The lobe 17' on the rotor 17 is entering the opposite recess in the rotor 16, and when the port 32 begins to overlap the port 25 (see Fig. 2) the gas in the recess will begin to discharge. Meanwhile,

the other lobe 16' on the rotor 16 will enter the corresponding recess in the rotor 17, the discharge of gas commencing when ports 27 and 34 overlap. By rotation of the plates 31 and 33 the timing of the opening of the ports can be varied, so varying the effective compression. Plates 31 and 33 are connected by links 22 and 23 to control means (not shown) which may be manual or automatic, e. g. a barometric capsule, or a boost control.

It will be appreciated that in the form described and shown in Figs. 1-4 since each rotor has two recesses there are two compression strokes per rotor per revolution.

Fig. 5 shows a compressor with rotors 16 and 17 each having a single lobe. With this form of rotor there is only one compression pulse per rotor per revolution and higher compressions are therefore obtainable in a compressor having such rotors. Otherwise the construction and operation of the compressor is as described in connection with Figs. 1 to 4.

Though the primary and intended use of the apparatus is as a compressor, and it has been described as such, it will be appreciated that a compressor constructed in accordance with the invention is reversible and will operate as a heat-engine. The disposition of the outlet ports in opposite end walls of the casing is particularly advantageous in a compressor because it permits of large outlet ports with no overlapping or interference with each other.

I claim:

1. A compressor comprising in combination a casing comprising side and end walls, said casing having at least one gas inlet passage in its side wall and having an outlet passage in each end wall, a pair of rotors each having mutually inter-engageable lobes and recesses said recesses forming gas transfer chambers, gearing for causing the rotors to rotate in opposite directions in such timed relationship that a lobe on one rotor enters a recess on the other rotor after said recess has passed the end of the inlet passage and before it reaches the end of the outlet passage, whereby gases are compressed during their transfer within said recess, each rotor having an integral ported web at one end, the webbed ends of the rotors being arranged at opposite ends of the casing, and the casing having a rotatably mounted ported plate at each end cooperating with the adjacent ported web of a rotor, and control means for adjusting the position of each ported plate within the casing whereby the timing of the overlap of the ports in said web and said plate may be adjusted.

2. A compressor comprising in combination a

casing having a body portion comprising a side wall with at least one gas inlet passage therein, an end cap attached to each end of the casing, each end cap having a gas outlet passage therein and secured to said body portion, a pair of rotors of identical non-circular and inter-engaging section mounted for rotation in opposite directions in said casing and mounted in said end caps and providing recesses between their inter-engaging portions whereby gas is transferred from the inlet passage to the outlet passage and compressed during its transfer in said recesses, one ported web mounted for rotation with each rotor at the end thereof, said webs being at opposite ends of the casing adjacent the respective end caps, a ported plate in each end cap contacting the adjacent ported web, said plate being rotatable within the end cap, and control means for controlling the angular position of said plates to adjust the timing of overlap of the ports in said webs and plates.

3. A compressor comprising a casing with parallel inter-communicating cylindrical bores closed by end caps, a pair of oppositely rotatable lobed inter-meshing impeller rotors in said bores, said rotors each having one ported end plate secured thereto adjacent opposite ends of the casing, two inlet ports respectively opening into the impeller-swept side walls of said bores to admit fluid to be compressed, outlet ports arranged in the end caps, one adjacent each ported end plate to release fluid which has been compressed, and a rotatable ported timing plate interposed between each of said outlet ports and the adjacent ported plate on the rotor to vary the compression within said casing.
